CLAIM

The ornamental design for a thermostat housing, as shown and described.

DESCRIPTION

FIG. 1 is a perspective view of a thermostat housing in accordance with the present invention;
FIG. 2 is a front side view of the thermostat housing of FIG. 1;

FIG. 3 is a left side view of the thermostat housing of FIG. 1;
FIG. 4 is a right side view of the thermostat housing of FIG. 1;

FIG. 5 is a top side view of the thermostat housing of FIG. 1; and,

FIG. 6 is a bottom side view of the thermostat housing of FIG. 1.

The broken line showing of structural features is included for the purpose of illustrating non-claimed subject matter and forms no part of the claimed design.

1 Claim, 6 Drawing Sheets
